UNITED STATES PATENT OFFICE.

PETER J. SMITH, OF CHICAGO, ILLINOIS, ASSIGNOR TO COMMONWEALTH EDISON COMPANY, OF CHICAGO, ILLINOIS, A CORPORATION OF ILLINOIS.

ELECTRICAL FUSE.

1,419,114.

Specification of Letters Patent. Patented June 6, 1922.

Application filed February 13, 1919. Serial No. 276,741.

To all whom it may concern:

Be it known that I, PETER J. SMITH, a citizen of the United States, residing at Chicago, in the county of Cook and State of Illinois, have invented a certain new and useful Improvement in Electrical Fuses, of which the following is a full, clear, concise, and exact description, reference being had to the accompanying drawings, forming 10 a part of this specification.

My invention relates to electrical fuses, particularly such as are employed in fusible cutouts and the like.

Fusible cutouts are employed in practice 15 to a great extent in primary circuits of distributing systems for protecting the circuits against overload. Such cutouts generally comprise a socket member and a plug member fitting thereinto. The socket member 20 generally has stationary contacts connected with the line and the plug member bears co-operating contacts connected by a fusible link. The particular form of the two members or the details of the cutout is no part of 25 my invention and I am explaining the general character of the same only in order to make clear the nature of the conditions under which a particular embodiment of my invention has proven to be highly successful.

Such cutouts are generally mounted on 30 poles or other exposed or semi-exposed mountings and as such are subject to atmospheric influences including moisture, acid and alkali fumes and the like.

The fusible link heretofore employed has 35 consisted generally of an aluminum ribbon connected between the contacts of the plug member. Considerable trouble has been experienced with corrosion of the fuse ribbon, 40 apparently due to an electrolytic action between the copper terminals and the aluminum, which action may be explained as follows.

The aluminum and copper are attacked by 45 air with the impurities contained therein forming salts on the surface of the metal. These salts, exposed to moisture, form an electrolyte in the presence of which a galvanic action is set up, causing the more electro-positive metal to become eaten away by 50 electrolysis.

Heretofore it has not been at all unusual to have the terminal portions of the fuse eaten away by the corrosive action to such 55 an extent as to greatly affect the carrying

capacity of the links. Such links cannot be made of the same material as the terminals with any degree of success and aluminum heretofore has proven the most suitable metal for the link.

According to my invention the ends of the link are reinforced by employing a double or multiple thickness of metal. Preferably this is secured in the ribbon type of fuse by folding the sheet material over to form a 60 double thickness at each end of the ribbon for about two inches in length to include the lug terminals. This insures the double advantage of compelling the fusible link to blow at the proper point when it is subjected to overload, and it further prevents the corrosion of the ends of the fuse from 65 affecting the capacity of the fuse.

My invention will be more readily understood from the following detail specification and drawings:

Figure 1 is a vertical axial section of the well known form of fusible cutout employing a fuse of my invention;

Figure 2 is a plan view of a fuse embodying my invention; and

Figure 3 is a plan view of a blank before folding.

The cutout shown in Figure 1 comprises the plug member 1 and the socket member 2. 85 The plug member 1 is provided with a suitable handle 3 whereby the same may be withdrawn from the socket 2. The socket 2 is supported by suitable lag screws shown at 4 passing through a part of the socket member. Suitable terminals 5 are mounted within the socket member 2 for making connections with line wires which pass through the 90 petticoat of the socket member at the openings 6.

Suitable stationary contact members connected to the terminals 5 are adapted to make contact with the plug contact members 8. The plug contact leads are provided with suitable terminal portions 9, to which said 100 terminal portions are fastened the ends 10 of the fusible links 12. The fusible link is thus put in series with the line and is adapted to be blown and thus to sever the continuity of the line upon the occurrence of over-load conditions. The plug member 1 may be withdrawn for renewing the fuse and may be inserted after the fuse has been renewed 105 to close the line.

The fuse 12, which has clamping terminals 110

10 and 11, is formed of sheet metal having a single thickness along the central portion as shown at 14, where the blowing of the fuse is adapted to occur and it is provided with 5 a double thickness of sheet metal along the end portions, including the clamping terminals 10 and 11. The manner of securing this double thickness is illustrated in Figure 3, which shows the flange prior to folding 10 together the end of the fuse.

The blank shown in Figure 3 comprises the intermediate portion 14 which is adapted to be blown by overload. This portion consists of a thin ribbon-like strip of sheet 15 aluminum. At the ends of the intermediate portion, the terminal portion is formed in duplicate, adapted to be folded along the line 15 which is a continuation of one edge of the intermediate portion 14. The folding 20 portions 17 and 18 are folded on the lines 15 and 16 respectively to form a double thickness of sheet metal at the terminal portions. I have shown the end portions as formed of greater width than the intermediate portions. 25 While this is preferable, it is not essential. The formation of the clamping lugs 10 and 11 in the shape illustrated, may occur after folding as well as before folding. This is a detail of manufacture which is immaterial. 30 The diagonal slots 19 and 20 extend away from the folded edge and provide easy means for attaching the link to the terminals. The ends and slots are symmetrical so that either end may be attached first.

35 It is apparent that instead of a single fold at the end portions, further folds may be formed to increase the thickness if desired.

The fuse of my invention is particularly

useful in cutouts, but I am aware that the invention is applicable to fuses for any other 40 type of apparatus. The fuse is preferably made up of sheet metal of substantially uniform thickness such as is found in the market at present, so that the construction of the fuse itself may be easy and inexpensive. 45

I claim:

1. A flat sheet metal fuse having an intermediate portion and an end portion, the intermediate portion comprising a narrow flexible strip of single thickness of sheet metal the 50 end portion comprising plural thicknesses of sheet metal integral with the intermediate portion, one thickness being a continuation longitudinally of the intermediate portion and the other thickness being a lateral continuation of said first continuation and being folded over upon said first continuation along a line running longitudinally of the fuse to produce an attaching terminal for the fuse. 55

2. A sheet metal fuse comprising a narrow flexible intermediate portion of a single thickness of sheet metal and end portions of greater width and thickness said end portions being formed of integral extensions at the ends of the intermediate portion folded flat 65 together in substantially the same plane as the intermediate portion, the folded edge at each end being substantially in line with an edge of the intermediate portion said folded portions forming quick detachable lugs projecting laterally from the edge remote from the folded edge. 70

In witness whereof I hereunto subscribe my name this 11th day of February, 1919.

PETER J. SMITH.
